United States Patent Office

Des. 194,136
Patented Nov. 20, 1962

194,136

ELECTRIC BROILER

Henry H. Rothman, Jackson Heights, N.Y.
(83-45 Broad, Elmhurst 73, N.Y.)

Filed Nov. 17, 1960, Ser. No. 62,885

Term of patent 14 years

(Cl. D81—10)

FIG. 1

FIG. 2

FIG. 3

FIGURE 1 is a front perspective view of an electric broiler embodying my new design,

FIG. 2 is a front elevational view of the electric broiler, and

FIG. 3 is a vertical sectional view of the electric broiler as viewed on line 3-3 of FIG. 2.

The rear is substantially plain as indicated in FIG. 3.

I claim:

The ornamental design for an electric broiler, substantially as shown and described.
